J. J. LARMOUR

POWDER CONTAINER

Filed March 21, 1924

Inventor:

James J. Larmour,
By his Attorney, Geo. F. Math

UNITED STATES PATENT OFFICE.

JAMES J. LARMOUR, OF NEW YORK, N. Y.

DESIGN FOR A POWDER CONTAINER.

Application filed March 21, 1924. Serial No. 9,015. Term of patent 7 years.

To all whom it may concern:

Be it known that I, JAMES J. LARMOUR, a citizen of the United States, residing in the borough of Manhattan, city, county, and State of New York, have invented a new, original, and ornamental Design for a Powder Container, of which the following is a specification, reference being had to the accompanying drawing, forming part thereof.

The figure is a perspective elevation of a container, showing my new design.

I claim:

The ornamental design for a powder container, as shown.

JAMES J. LARMOUR.

Witnesses:

GEO. WM. MIATT,
MATHILDA STEUERNAGEL.
